CONTROLLING MEANS

Arthur Persson, Painesville, Ohio

Application October 21, 1939, Serial No. 300,613

13 Claims. (Cl. 277—32)

This invention relates to means for controlling flow of fluids and is particularly applicable to the flow of fluids which have destructive effects upon apparatus of existing types.

In many industrial processes it is necessary to handle fluids, either in liquid or gaseous form, which have highly destructive properties with regard to the valves and other structures through which these fluids must pass.

As examples of such fluids, attention may be called to various acid and alkaline solutions entering in various manners into chemical processes. Some of these materials are highly corrosive to the various metals and alloys of which the control valves and the like are made, some have highly erosive effects thereon, and some, particularly those which are of a saturated nature or which carry material in suspension, have a tendency to clog apparatus if their velocity be diminished, while many possess two or more of the properties above described.

For these reasons it has been found extremely difficult, and at times practically impossible, accurately to control such fluids with the common types of valves, while at the same time in many of the processes in which the fluids are employed, precision of control of the flow is extremely essential.

This control has been obtained by various expedients, which have overcome only in part the difficulties encountered.

For example: in certain chemical processes where liquid solutions capable of precipitating solid material and having both high corrosive and erosive properties must be accurately throttled, the ordinary types of globe, angle and gate valves have been found to clog to such an extent as to render their use prohibitive.

To overcome the clogging, valves of the stop cock type have been substituted, and these are closed partially to throttle the flow of the liquid.

While this substitution to an extent relieves the difficulties of clogging, valves of this type increase the friction opposing the flow of the fluid, and become rapidly worn where the flow passes the projecting edges of the valve plug, requiring frequent and expensive replacement.

The exactitude of control by such means also leaves much to be desired. However, their use has been resorted to as presenting less evils than were possessed by apparatus of other known types.

It is an object of my invention to provide a control apparatus which will eliminate the vari-

ous disadvantages above described and others attendant upon the use of prior types of fluid controlling apparatus.

The invention will be better understood from the description of one practical embodiment thereof, illustrated in the accompanying drawing, in which:

Figure 1 is the side elevation of a controlling mechanism, resembling in general dimensions a valve, and embodying my invention;

Figure 2 is a transverse sectional view thereof taken on line II—II of Figure 1; and

Figure 3 is a horizontal cross sectional view taken on the line III—III of Figure 1.

The apparatus illustrated consists of a main body or frame which conveniently may be a casting comprising a generally cylindrical portion 1 containing a control mechanism and which is provided at its ends with flanges 2 and 3 by which it may be connected to flanges on the ends of sections on a pipe line or other conduit, as is well understood in the art.

The interior of the body 1 is formed into a generally conical vertical recess 4, with which communicate two passages 5 and 6 opening generally concentrically of the flanges 2 and 3.

Positioned within the recess 4 is a frusto-conical plug 7, the bottom of which terminates slightly above the bottom of the recess, and which is reduced adjacent the top of the body portion by a radially extending shoulder 8 to form an upwardly extending cylindrical neck or stem 9 passing to a substantial distance above the body of the device. The projecting end of the stem is squared for a purpose hereinafter indicated.

The plug has a diametric passage 10 extending therethrough and adapted to be brought into alignment with the ends of the openings 5 and 6 from the ends of the body, and with these to form a direct passage through the device. This passage is best seen in Figure 3, and presents, in longitudinal section, the shape of a venturi.

Surrounding the stem of the plug is packing material 11, received in an annular recess 12 in the top of the body, and held in place by a packing gland 13 clamped upon the body by means of threaded studs 14 and nuts 15. The packing gland is provided on its upper surface with two projecting lugs 16 adapted to engage a corresponding lug 17 formed upon a stop collar 18 mounted upon the stem 9 and caused to rotate therewith by reason of the squared shape of this upper end of the stem.

The square end of the stem is also engaged

by a wrench or handle 18 by which it may be rotated.

Thus it will be apparent, with the lugs 16 and 17 properly spaced, that these will limit the rotation of the plug 7 from the position shown in Figure 3, where it forms a smooth continuance of passages 5 and 6, to a position at right angles to this position where it completely closes the passage.

A central bore or hole extends through the stem of the plug, communicating with the passage 10 therethrough, and is internally threaded as indicated at 20 throughout a substantial portion of its extent.

Passing through this bore is a shaft 21 having a short external thread 22 conjugate to and engaging the internal thread 20 in the plug stem.

The upper end of the shaft is reduced and squared at 23 and has secured to it a hand wheel 24 held in place by a nut 25 threaded onto the shaft, by which hand wheel the shaft may be rotated to move it up or down as desired.

The lower end of the shaft is reduced in diameter as indicated at 26 and surrounded by a ferrule-like tip 27 which may project into and thus obstruct the opening through the plug.

This tip may be secured to the shaft in any desired manner, as by being shrunk thereon, welded or brazed thereto, or by threads, or it may be formed unitarily with the shaft if the latter be of a material which is relatively free from attack by the fluid which will pass through the device.

It will also be apparent that tips of different diameter may be provided and one substituted for another upon the end of the shaft if different problems of control are to be met by the apparatus.

Surrounding the upper end of the shaft in a recess in the upper end of the plug stem is a packing 28 held in place by a packing gland 29 threaded into the upper end of the stem.

A fitting 30 is threaded into an aperture in the bottom of the body, this being of a type which will permit the injection of grease or other lubricant under pressure.

Two upwardly extending grooves 31 are cut into the body extending from the bottom of the plug nearly to the top of the body, and being positioned closely adjacent the edges of the openings 5 and 6. The upper ends of these grooves are positioned to communicate with a diametric hole 32 drilled through the plug, which in turn communicates with a vertical hole 33 passing to the top of the plug stem, its upper end being sealed as by means of a screw plug 34. A radial hole 35 intersects the vertical hole near its top and communicates with the central aperture immediately below the packing gland.

Thus, it will be apparent that lubricant may be transmitted through the body and the holes in the plug to the threads in the plug stem 9 above those on the shaft 21 and also to the lower part of the threads in the plug stem.

Consequently, whenever the shaft 21 is moved up or down by a rotation of the hand wheel, lubricant is forced from within the stem through the holes, to keep the threads and shaft thoroughly lubricated, and also lubricant is spread over the contacting and engaging surfaces of the plug and body.

In use, the wrench is used to move the plug into only one of two positions: i. e., fully open, as illustrated in Figure 3, or fully closed. When in fully open position, the passage through

the body and plug is continuous, without projecting or abrupt edges, and is in effect a venturi, causing the fluid to flow most rapidly while passing through the plug.

5 Thus any tendency to deposit solid particles within the device is eliminated, but these are scavenged or swept through at an even higher velocity than that traveled through the conduits to and from the device. Due to the stream line

10 Venturi shape, erosion is greatly reduced and the high velocity of the fluid likewise inhibits or reduces any corrosive or galvanic action.

When it is desired to partially restrain the fluid passing through the device, this is accom-

15 plished by adjustment of the hand wheel, moving the tip on the lower end of the shaft into the passage through the plug to any desired extent. The projecting tip, of course, reduces the effective cross sectional area of passage through

20 the plug, but even when moved to its most extreme position where it touches the bottom of the opening, still permits the fluid to pass directly on both sides of the tip. The cylindrical shape of the tip permits the fluid to pass freely

25 around, and the fluid, of course, in passing between the sides of the tip and the side walls of the plug, must move at its maximum velocity, precluding any deposit of material on the tip itself.

30 It will be apparent that, should it be desired to remove or change the shaft or tip, it is only necessary by use of the wrench to shut off the device completely, then to remove the upper packing gland, and to rotate the hand wheel and

35 the shaft, and that all this may be done without requiring any disconnection between the conduit line and the body of the apparatus.

As the plug is moved only when it is desired to completely shut off the apparatus, wear between it and the body is reduced to a minimum.

40 It will, therefore be apparent that the life of the device is long in service, and that replacements of the valve tip or shaft may be made many times before it is necessary to shut down

45 the line to replace the entire device.

While I have described the illustrated embodiment of this invention in some particularity, obviously many others will readily occur to those skilled in this art, and I do not, therefore, limit myself to the precise details shown and described, but claim as my invention all embodiments, variations, and modifications thereof coming within the scope of the appended claims.

I claim:

55 1. Fluid control means comprising a body having a passage therethrough, a movable member extending into the body and across the passage, said member having a passage therethrough which when brought into alignment

60 with that through the body forms a streamline continuation thereof, a second member movable into the passage through the first mentioned member, the portion of the second member which enters said passage being spaced from the sides of the passage and of streamline shape whereby fluid passing through the passage at all times scavenges all exposed surfaces of both members.

65 2. Fluid control means comprising a body having a passage of generally Venturi shape therethrough, a movable member extending into the body and across the passage, said member

70 having a passage therethrough which when brought into alignment with that through the body forms a streamline continuation thereof, a

second member movable into the passage through the first mentioned member, the portion of the second member which enters said passage being spaced from the sides of the passage and of streamline shape whereby fluid passing through the passage at all times scavenges all exposed surfaces of both members.

3. Fluid control means comprising a body having a passage of generally Venturi shape therethrough, a movable member extending into the body and across the passage, said member having a passage therethrough which when brought into alignment with that through the body forms a streamline continuation thereof and constitutes the throat of the venturi, a second member movable into the passage through the first mentioned member, the portion of the second member which enters said passage being spaced from the sides of the passage and of streamline shape whereby fluid passing through the passage at all times scavenges all exposed surfaces of both members.

4. Fluid control means comprising a body having a passage therethrough, a rotatable member extending into the body and across the passage, said member having a passage therethrough which when brought into alignment with that through the body forms a streamline continuation thereof, a second member movable into the passage through the first mentioned member, the portion of the second member which enters said passage being spaced from the sides of the passage and of streamline shape whereby fluid passing through the passage at all times scavenges all exposed surfaces of both members.

5. Fluid control means comprising a body having a passage therethrough, a rotatable member extending into the body and across the passage, said member having a passage therethrough which when brought into alignment with that through the body forms a streamline continuation thereof, a second member axially movable into the passage through the first mentioned member, the portion of the second member which enters said passage being spaced from the sides of the passage and of streamline shape whereby fluid passing through the passage at all times scavenges all exposed surfaces of both members.

6. Fluid control means comprising a body having a passage therethrough, a movable member extending into the body and across the passage, said member having a passage therethrough which when brought into alignment with that through the body forms a streamline continuation thereof, the sides, top and bottom of the passage being smooth and continuous, a second member movable into the passage through the first mentioned member, the portion of the second member which enters said passage being spaced from the sides of the passage and of streamline shape whereby fluid passing through the passage at all times scavenges all exposed surfaces of both members.

7. Fluid controlling means comprising a body defining a direct continuous opening therethrough and a recess having partially conical sides, a partially conical plug rotatable in the recess, a handle for rotating said plug, the plug having an opening therethrough which when brought into alignment with the opening through the body forms a continuous smooth wall Venturi-like passage, the plug when rotated to bring its passage out of alignment with that of the

body being capable of completely closing the latter, a rod threaded into the plug and extensible axially into the passage, the portion of the rod extensible into said passage being spaced substantially from the sides thereof and the end of the rod being streamline in shape to produce only streamlined spaces at the sides and end of the rod whereby the fluid flowing through the passages scavenges all exposed surfaces of the passages and of the rod.

8. Fluid control means comprising a body having a passage therethrough, a movable member extending into the body and across the passage, said member having a passage therethrough which when brought into alignment with that through the body forms a streamline continuation thereof, the passage through the member being of less cross sectional area than the greatest cross sectional area of the passage through the body, a second member extending into the passage through the first mentioned member and at all times confining fluid to the streamline passages through the body and first member and selectively movable into said passage, the portion of the second member which enters said passage being spaced from the sides of the passage and of streamline shape whereby fluid passing through the passage at all times scavenges all exposed surfaces of both members.

9. Fluid control means comprising a body having a passage of generally Venturi shape therethrough, a movable member extending into the body and across the passage, said member having a passage therethrough which when brought into alignment with that through the body forms a streamline continuation of said Venturi shaped passage, the passage through the member being of less cross sectional area than the greatest cross sectional area of the passage through the body, a second member movable into the passage through the first mentioned member, the portion of the second member which enters said passage being spaced from the sides of the passage and of streamline shape whereby fluid passing through the passage at all times is confined to the streamline passage through the body and the first mentioned member and so scavenges all exposed surfaces of both members.

10. Fluid control means comprising a body having a passage therethrough, a rotatable member extending into the body and across the passage, said member having a passage therethrough which when brought into alignment with that through the body forms a streamline continuation thereof, there being a perforation extending through said member and communicating with the passage therethrough, the passage through the member being of less cross sectional area than the greatest cross sectional area of the passage through the body, a second member filling the perforation and having an end extending into the passage through the said first mentioned member and selectively movable into said passage confining the fluid to the streamline passage through the body and first mentioned member, the portion of the second member which enters said passage being spaced from the sides of the passage and of streamline shape whereby fluid passing through the passage at all times scavenges all exposed surfaces of both members.

11. Fluid control means comprising a body having a passage therethrough, a rotatable member extending into the body and across the passage, said member having a passage there-

through which when brought into alignment with that through the body forms a streamline continuation thereof, there being a perforation extending through said member and communicating with the passage therethrough, the passage through the member being of less cross sectional area than the greatest cross sectional area of the passage through the body, a second member filling the perforation and having an end extending into the passage through the said first mentioned member and selectively axially movable into said passage confining the fluid to the streamline passage through the body and first mentioned member, the portion of the second member which enters said passage being spaced from the sides of the passage and of streamline shape whereby fluid passing through the passage at all times scavenges all exposed surfaces of both members.

12. Fluid control means comprising a body having a passage therethrough, a movable member extending into the body and across the passage, said member having a passage therethrough which when brought into alignment with that through the body forms a streamline continuation thereof, the passage through the member being of less cross sectional area than the greatest cross sectional area of the passage through the body, the sides, top and bottom of the passage being smooth and continuous, a second member movable into the passage through the first mentioned member, the portion of the

second member which enters said passage at all times constituting an inward projection from the smooth and continuous surface of the passage and being spaced from the sides of the passage and of streamline shape whereby fluid passing through the passage at all times scavenges all exposed surfaces of both members.

13. Fluid controlling means comprising a body defining a direct continuous passage therethrough and a recess having partially conical sides, a partially conical plug rotatable in the recess, a handle for rotating said plug, the plug having a passage therethrough which when brought into alignment with the passage through the body forms a continuous smooth wall Venturi-like passage, the passage through the plug being of less cross sectional area than the greatest cross sectional area of the passage through the body, the plug when rotated to bring its passage out of alignment with that of the body being capable of completely closing the latter, a rod threaded into the plug and extensible axially into the passage, the portion of the rod extensible into said passage being spaced substantially from the sides thereof and the end of the rod being streamline in shape to produce only streamlined spaces at the sides and end of the rod whereby the fluid flowing through the passage scavenges all exposed surfaces of the passages and of the rod.

ARTHUR PERSSON.
